US0D1042608S

(12) **United States Design Patent** (10) **Patent No.:** **US D1,042,608 S**
(45) **Date of Patent:** **** Sep. 17, 2024**

(54) **GLASSES**

(71) Applicant: **Xiamen Xutu Optical Glasses Co., Ltd.**, Fujian (CN)

(72) Inventor: **Jiqiang Gong**, Fujian (CN)

(73) Assignee: **Xiamen Xutu Optical Glasses Co., Ltd.**, Xiamen (CN)

(**) Term: **15 Years**

(21) Appl. No.: **29/912,833**

(22) Filed: **Sep. 25, 2023**

(30) **Foreign Application Priority Data**

Mar. 24, 2023 (CN) 202330149157.0

(57) **CLAIM**

The ornamental design for glasses, as shown and described.

DESCRIPTION

FIG. 1 is a front elevational view of glasses showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a perspective view thereof;

FIG. 8 is an enlarged view of the encircled portion '8' in FIG. 2; and,

FIG. 9 is an enlarged view of the encircled portion '9' in FIG. 7.

The broken lines shown in the drawings are for the purpose of illustrating portions of the article and form no part of the claimed design.

1 Claim, 9 Drawing Sheets
